UNITED STATES PATENT OFFICE

111,608

DESIGN FOR A STOOL

Karl Kipp, Olean, N. Y., assignor to Daystrom Corporation, Olean, N. Y., a corporation of New York

Application July 19, 1938, Serial No. 78,591

Term of patent 3½ years

To all whom it may concern:

Be it known that I, Karl Kipp, a citizen of the United States, residing at Olean, in the county of Cattaraugus and State of New York, have invented a new, original, and ornamental Design for a Stool, of which the following is a specification, reference being had to the accompanying drawing, forming part thereof; and in which

I claim:

The ornamental design for a stool substantially as shown.

KARL KIPP.
